US0D1000980S

(12) **United States Design Patent** (10) **Patent No.:** **US D1,000,980 S**
(45) **Date of Patent:** **** Oct. 10, 2023**

(54) **POSITIONING TRACKER**

(71) Applicant: **Acer Incorporated**, New Taipei (TW)

(72) Inventors: **Jung-Wei Tsao**, New Taipei (TW);
Ker-Wei Lin, New Taipei (TW);
Wei-Chang Chen, New Taipei (TW)

(73) Assignee: **Acer Incorporated**, New Taipei (TW)

(**) Term: **15 Years**

(21) Appl. No.: **29/809,796**

(22) Filed: **Sep. 30, 2021**

(30) **Foreign Application Priority Data**

May 11, 2021 (TW) 110302442

(51) **LOC (14) Cl.** **10-04**

(52) **U.S. Cl.**
USPC **D10/65**

(57) **CLAIM**

The ornamental design for a positioning tracker, as shown and described.

DESCRIPTION

FIG. 1 is a perspective view of a positioning tracker showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate portions of the positioning tracker that form no part of the claimed design.

1 Claim, 6 Drawing Sheets
